DOOR HANGER STRUCTURE

Don R. Danley, Mendon, Mich.

Application October 16, 1935, Serial No. 45,176

18 Claims. (Cl. 16—87)

This invention relates to improvements in door hanger structures.

The main objects of this invention are:

First, to provide an improved sliding door hanger structure particularly well adapted for barns, stables, garages and the like, although it is well adapted for use on freight cars, delivery vehicles, or the like.

Second, to provide a sliding door structure in which the track is completely enclosed thereby protecting the parts from the elements and also preventing birds and animals from building nests therein and obstructing the opening of the door.

15 Third, to provide a sliding door structure which is characterized by substantially frictionless operation, yet is sturdy and a wear resisting structure.

Fourth, to provide a sliding door hanger structure which is easily assembled and easily attached to the building, and may be very economically manufactured.

20 Objects pertaining to details and economies of my invention will definitely appear from the description to follow. The invention is defined in the claims.

A structure which embodies the features of my invention is clearly illustrated in the accompanying drawing, in which:

25 Fig. 1 is an enlarged fragmentary vertical section along line 1—1 of Figs. 2 and 3 of a door hanger structure embodying the features of my invention.

Fig. 2 is a fragmentary perspective view there- 30 of.

Fig. 3 is a fragmentary view partially in section on line 3—3 of Fig. 1.

Fig. 4 is a perspective view of a modified form of bearing support.

40 Fig. 5 is a fragmentary view partially in section through the track and hanger of the modified form of my invention.

Fig. 6 is a front elevation of a sliding door equipped with my improved hanger.

45 Objections to known types of hanger structure for sliding doors of the type employed on barns, stables or vehicles such as freight cars, etc., lie in the fact that they are open to the elements or that their open structure furnishes a place in which birds and animals may gain ready access to build nests or otherwise impede the operation thereof. Further, they are complicated in structure and present difficulties in assembly as well as expense in manufacture which is not desirable 50 in a device intended for cheap marketing. Also,

due to the rough usage to which said structures are subjected, a device embodying maximum strength along with simplicity of structure is also to be very greatly desired. The embodiments of my invention which I have chosen for illustration possess characteristics which overcome the above noted defects in the prior known door hanger structures.

Referring to the drawing, reference numeral 1 indicates a building provided with a sliding door 10 2. The track member or element of my improved sliding door hanger structure designated generally by the numeral 3 consists of a tubular track portion 4, a housing portion 5 and a web-like hanger portion 6. This track member is formed of an 15 elongated strip of sheet metal suitably conformed to provide these parts. The web-like attaching portion 6 is longitudinally ribbed at 7 to stiffen the same. The housing portion 5 extends outwardly and downwardly from the lower edge of the attaching portion 6 and terminates in a scroll-like roll 8 terminating in the tubular track 4, this tubular track being the inner convolution of the scroll or spiral roll. The track 4 has spaced openings 9 in its top surrounded by upwardly tapered flanges 10 receiving the ball bearing members 11. The diameter of the openings is less than the diameter of the balls so that the balls are retained within the openings to project therefrom as illustrated.

30 The balls are supported by bearing members 12 preferably of anti-friction composition, a fibrous composition being very satisfactory. These are supported by the C shaped spring supports 13 which are slidable longitudinally within 35 the track and may be compressed sufficiently to permit the bearing members with the bearings therein to slide along the track until a bearing member is brought opposite one of the bearing openings in the track when the parts will properly position themselves.

In the modification shown in Figs. 4 and 5 the bearing openings 14 in the track are elongated to receive the barrel-shaped bearings 15. The bearing members 16 in this embodiment are 45 also C shaped, being arranged to embrace the bearings 15 and having bearing openings 17 therein registering with the openings 14 in the track. The lugs 18 are struck inwardly from the arms of the support 18' to support the bearing 50 box.

55 The door hanger member designated generally by the numeral 19 is also formed of an elongated strip of sheet metal which is conformed to provide a cylindrically curved slide member 20 em-

bracing the track and riding upon the bearings thereof. The strip is also shaped to provide an angled door attaching member 21 which fits over the upper edge of the door and is secured upon the face thereof as by means of screws or bolts 22. The attaching web 6 and the attaching web 21 are both perforated at suitable intervals to receive the attaching screws. I have illustrated the attaching portions as being web-like or continuous but they may be divided or portions cut out to reduce weight and save material, that is the attaching portions might be in the form of straps with satisfactory results but I prefer the web-like attaching portions. As is apparent from the structure illustrated embodying my invention, the track, slide and bearings are completely encased.

The structure is very economical to produce and the bearing members may be readily formed of self-lubricating frictionless material, thereby avoiding the necessity of lubrication and promoting long life. The structure is also substantially noiseless.

I provide an end plate 23 at one end of the track member, this serving as a stop and also closing the housing at that end. The slide moves freely without binding engagement and it can adjust itself freely to any conditions arising from warpage or non-alinement. The housing effectively protects the bearing parts from weather and also birds and animals are effectively excluded.

The structure may be made very compact, that is, the housing can be made to so closely fit the slide that it is impossible for a bird or animal to find access. There should be sufficient room, however, so that the slide is free to adjust itself on the bearings and contacts only therewith.

I have illustrated and described my invention in embodiments which I have found very practical. I have not attempted to illustrate and describe other embodiments and adaptations which I contemplate as I believe this disclosure will enable those skilled in the art to embody or adapt my improvements as may be desired.

Having thus described my invention what I claim as new and desire to secure by Letters Patent is:

1. In a door hanger structure, the combination of a track member formed of an elongated strip of sheet metal conformed to provide an upper web-like attaching portion, an intermediate outwardly and downwardly inclined housing portion terminating in a spiral, the inner convolution of which is of substantially cylindrical cross section and constitutes a track supported within the housing, the track having spaced bearing openings at the top thereof surrounded by upwardly tapered flanges, segmental bearing members of composition self-lubricating material having concaved bearing seats disposed within said track in opposed relation to said bearing openings, said bearing members being provided with spring supports, bearings arranged in said bearing members to project through said openings in said track, and a door hanger member formed of an elongated strip of sheet metal conformed to provide a cylindrically curved slide member embracing said track and an angled web-like door attaching portion.

2. In a door hanger structure, the combination of a track member formed of an elongated strip of sheet metal conformed to provide an upper web-like attaching portion, an intermediate outwardly and downwardly inclined housing por-

tion terminating in a spiral, the inner convolution of which is of substantially cylindrical cross section and constitutes a track supported within the housing, the track having spaced bearing openings at the top thereof, bearing members having concaved bearing seats disposed within said track in opposed relation to said bearing openings, bearings arranged in said bearing members to project through said openings in said track, and a door hanger member formed of an elongated strip of sheet metal conformed to provide a cylindrically curved slide member embracing said track and an angled web-like door attaching portion.

3. In a door hanger track structure, the combination of a track member formed of an elongated strip of sheet metal conformed to provide an upper web-like attaching portion, an intermediate outwardly and downwardly inclined housing portion terminating in a spiral, the inner convolution of which is of substantially cylindrical cross section and constitutes a track supported within the housing, the track having spaced bearing openings at the top thereof surrounded by upwardly tapered flanges, segmental bearing members of composition material having concaved bearing seats disposed within said track in opposed relation to said bearing openings, said bearing members being provided with spring supports, and bearings arranged in said bearing members to project through said openings in said track.

4. In a door hanger track structure, the combination of a track member formed of an elongated strip of sheet metal conformed to provide an upper web-like attaching portion, an intermediate outwardly and downwardly inclined housing portion terminating in a spiral, the inner convolution of which is of substantially cylindrical cross section and constitutes a track supported within the housing, the track having spaced bearing openings at the top thereof, and bearings arranged to project through said openings in said track.

5. In a door hanger track structure, the combination of a track member comprising an upper web-like attaching portion, an intermediate housing portion terminating in an inturned coil constituting a track supported within the housing, the track having spaced bearing openings at the top thereof, bearing members disposed within said track in opposed relation to said bearing openings, bearings arranged in said bearing members to project through said openings in said track, and a door hanger member comprising a cylindrically curved slide member embracing said track and a door attaching portion extending from the inner edge of said slide member.

6. In a door hanger structure, the combination of a track member comprising a housing portion terminating in an inturned coil constituting a track supported within the housing, the track having spaced bearing openings at the top thereof, bearings arranged to project through said openings in said track, and a door hanger member comprising a cylindrically curved slide member embracing said track and a door attaching portion extending from the inner edge of said slide member.

7. In a door hanger structure, the combination of a track member comprising a housing portion terminating in an inturned coil constituting a track supported within the housing, the track having spaced bearing openings at the top

thereof surrounded by upwardly tapered flanges, bearing members having bearing seats disposed within said track in opposed relation to said bearing openings, and bearings arranged in said bearing members to project through said openings in said track.

8. In a door hanger structure, the combination of a track member comprising a housing portion terminating in an inturned coil constituting a track supported within the housing, the track having spaced bearing openings at the top thereof, and bearings arranged to project through said openings in said track.

9. In a door hanger structure, the combination of a track member comprising an upper web-like attaching portion, an intermediate housing portion terminating in an inturned coil constituting a track supported within the housing, the track having spaced bearing openings at the top thereof, and bearings arranged to project through said openings in said track, said openings being smaller than said bearings whereby the bearings are restrained in the track.

10. In a door hanger structure, the combination of a tubular track formed of sheet metal rolled upon itself, one edge of the track being extended to provide a housing disposed above the track, said track having spaced openings in the top thereof, bearing members arranged in said openings, supporting bearings for said bearing members arranged within the track, said supporting bearings being provided with C-shaped spring metal supports, and a coacting sheet metal hanger comprising a curved slide portion arranged within said housing to embrace said track and slidably supported on said bearings.

11. In a door hanger structure, the combination of a tubular track formed of sheet metal rolled upon itself, one edge of the track being extended to provide a housing disposed above the track, said track having spaced openings in the top thereof, bearing members arranged in said openings, and a coacting sheet metal hanger comprising a curved slide portion arranged within said housing to embrace said track and slidably supported on said bearings.

12. In a door hanger structure, the combination of a tubular track formed of sheet metal rolled upon itself, one edge of the track being extended to provide a housing disposed above the track and an attaching web extending from said housing, said track having spaced openings in the top thereof, bearing members arranged in said openings, a coacting sheet metal hanger comprising a curved slide portion arranged within

said housing to embrace said track and slidably supported on said bearings, and an offset door attaching web or strap.

13. In a door hanger track structure, the combination of a tubular track having spaced openings in the top thereof surrounded by a tapered flange, bearing members arranged in said openings, and supporting bearings for said bearing members arranged within the track, said supporting bearings being provided with C-shaped spring metal supports.

14. In a door hanger track structure, the combination of a tubular track having spaced openings in the top thereof, bearing members arranged in said openings, and supporting bearings for said bearing members arranged within the track and resiliently urging said bearing members toward said openings.

15. In a door hanger track structure, the combination of a tubular track having spaced openings in the top thereof, bearing members arranged in said openings, and supporting bearings of fibrous self-lubricating material for said bearing members arranged within the track.

16. In a door hanger structure, the combination of a tubular track having spaced openings in the top thereof, bearing members arranged in said track to project through said openings, and a coacting hanger comprising a curved slide portion embracing said track and slidably supported on said bearings.

17. In a door hanger structure, the combination of a tubular track having spaced transversely disposed elongated openings in the top thereof, barrel-shaped bearing members arranged in said openings to project from the track, supporting bearings of anti-friction material having bearing seats conformed to the bearing members supported within said track in opposed relation to the bearing openings thereof, and a coacting hanger comprising a curved slide embracing said track and slidably supported on said bearings, the curve of the track corresponding to the longitudinal curvature of the bearings.

18. In a door hanger structure, the combination of a tubular track having spaced transversely disposed elongated openings in the top thereof, barrel-shaped bearing members arranged in said openings to project from the track, and a coacting hanger comprising a curved slide embracing said track and slidably supported on said bearings, the curve of the track corresponding to the longitudinal curvature of the bearings.

DON R. DANLEY.
